UNITED STATES PATENT OFFICE

BONNIE E. LEMM, OF DETROIT, MICHIGAN, ASSIGNOR TO TERNSTEDT MANUFACTURING COMPANY, OF DETROIT, MICHIGAN, A CORPORATION OF MICHIGAN

DESIGN FOR A WINDOW-REGULATOR HANDLE OR THE LIKE FOR AN AUTOMOTIVE VEHICLE

Application filed December 14, 1929. Serial No. 33,788. Term of patent 7 years.

To all whom it may concern:

Be it known that I, BONNIE E. LEMM, a citizen of the United States, residing at 1120 Campbell Avenue, Detroit, in the county of Wayne and State of Michigan, have invented a new, original, and ornamental Design for a Window-Regulator Handle or the like for an Automotive Vehicle, of which the following is a specification, reference being made to the accompanying drawings, forming part thereof.

Fig. 1 is a front elevation showing my new design for a window regulator handle or the like for an automotive vehicle and Fig. 2 is a side elevation of the same.

I claim:

The ornamental design for a window regulator handle or the like for an automotive vehicle substantially as shown.

BONNIE E. LEMM.
